UNITED STATES PATENT OFFICE.

LAURA GEROULD CRAIG, OF BUFFALO, NEW YORK, ASSIGNOR TO THE CHRISTIAN WOMAN'S BOARD OF MISSIONS, OF INDIANAPOLIS, INDIANA.

DESIGN FOR A BADGE.

SPECIFICATION forming part of Design No. 30,328, dated March 14, 1899.

Application filed August 29, 1898. Serial No. 689,813. Term of patent 14 years.

To all whom it may concern:

Be it known that I, LAURA GEROULD CRAIG, a citizen of the United States, residing at Buffalo, in the county of Erie and State of New York, have invented and produced a new and original Design for Badges, of which the following is a specification.

In the accompanying drawings, which form a part hereof, Figure 1 is a front elevation of my badge, and Fig. 2 a central horizontal sectional view of the same.

As shown in said drawings, the main body of the design for a badge involving my invention has a circular outline. Upon its face are intersecting lines of the character usually employed to indicate parallels and meridians upon maps, with representations of continents thereon in proper position, while across the same, about midway thereof, is a band on which a suitable inscription may be placed, and I have used as such inscription

the words "For Christ." Surrounding the portions just described is an ornamental scrollwork, forming, in effect, a setting for the badge. Such a badge may be understood to 25 symbolize the expressions "The World for Christ" or "The Americas for Christ," and forms a pleasing and attractive arrangement, constituting a very desirable badge for the members of a Christian society.

Having thus fully described my said invention, what I claim as new, and desire to secure by Letters Patent, is—

The design for a badge substantially as herein shown and described.

In witness whereof I have hereunto set my hand and seal, at Buffalo, New York, this 25th day of August, A. D. 1898.
